UNITED STATES PATENT OFFICE.

LEIF LEE, OF YOUNGSTOWN, OHIO.

HEATING FURNACE.

Application filed February 19, 1927. Serial No. 169,548.

This invention relates to heating furnaces and particularly for the heating of sheets, pairs of packs in sheet rolling.

I provide a simple and effective supporting means within a furnace chamber for heating the material, which is hereinafter referred to as "sheet material" for convenience.

I employ a support which is preferably in the form of a spider, and which is rotatable about a horizontally extending axis. In the preferred form the furnace chamber has an inlet and an outlet on diametrically opposite sides, the sheet material being fed into one side and out the other. During its travel through the furnace it lies between adjacent arms of the spider. As the spider rotates the sheet is carried from the horizontal position at which it enters the furnace up to a vertical position, and then is again returned to the horizontal position by continued rotation of the spider. The sheet material is delivered upside down relative to its position when it enters the furnace.

Preferably the heating means is arranged to provide a downward sweep of heating gases over the sheet material. My invention assures the uniform heating of the sheet material and there is no danger of them being delivered with black spots. The material is on edge during part of its travel through the furnace and therefore all loose surface material will fall off.

The spider is preferably cooled either by water or by air.

If desired, supplemental material handling means may be employed in connection with the spider. This supplemental handling means preferably takes the form of material engaging means lying between the arms of the spider and adapted for moving it in a direction other than the direction of rotation of the spider.

My improved furnace is preferably placed with the line of travel of the material through the furnace lying generally parallel to the axes of the sheet rolls. A doubler is preferably placed adjacent the furnace inlet. In this manner the material may be expeditiously handled and the entire rolling operation may be speeded up.

In the accompanying drawings which illustrate the present preferred embodiment of the invention,

Figure 1 is a vertical transverse section taken through a furnace embodying the invention and on the line I—I of Figure 2, and

Figure 2 is a vertical longitudinal section taken on the line II—II of Figure 1,

Referring to Figures 1 and 2, there is shown a furnace structure comprising a combustion chamber 2 and a heating chamber 3 divided by a bridge wall 4. The heating chamber 3 has a material inlet 5 and an outlet 6. The material is carried through the furnace by a spider which is mounted on a hollow shaft 7. The shaft is carried in bearings 8 and has an overhung portion which extends into the furnace. The shaft carries a worm wheel 9 meshing with a worm 10 driven from any suitable source of power.

The overhanging end of the shaft 7 carries a hub casting 11. This casting has a central portion 12 and spaced apart flanged portions 13. The arms of the spider are made of U-shaped members 14 tangentially arranged about the hub casting 11. These members may be made of bar stock or of tubing, as desired.

The sheet material S is supplied through the opening 5 and rests on one of the spider arms 14. The spider rotates in a clockwise direction as viewed in Figure 1 and the material is gradually moved toward the vertical position as the spider carries it upwardly. The edge of the sheet engages the peripheries of the flanges 13. When the sheet material passes the vertical plane intersecting the axis of the shaft 7, it "flops" from engagement with one arm of the spider into engagement with the adjacent arm. This is shown in Figure 1. This movement aids in the removal of loose or adherent material from the surface of the sheets. It also exposes to the combustion gases those portions of the sheet material which were first in engagement with a spider arm, thus ensuring the absence of black spots from the heated material.

The combustion gases sweep over the bridge wall 2 and move downwardly through the combustion chamber 3 to outlets 15 communicating with a stack connection 16.

A central tube 17 extends within the hollow shaft 7 to a point adjacent its inner end. A cooling fluid, such as air or water, may be supplied therethrough to cool the shaft and the spider. It is not desirable to cool the flanges 13 or the U-shaped arms 14 excessively, as this would produce black spots on the sheet material. Accordingly, I prefer to employ spacers on the arms. These spacers take the form of washer-like members 18 made of sheet material and placed over the outside of

the pipe from which the spider is made. They hold the sheet material out of direct contact with the cool spider arm and thus prevent black spots.

5 While I have shown and described the present preferred form of my invention, it will be understood that it may be otherwise embodied within the scope of the following claims:

I claim:—

10 1. In a heating furnace, a spider having arms adapted for supporting material in the furnace, means whereby the arms may be

cooled and spacers on the arms effective for holding material spaced from the cooled portion.

15

2. In a heating furnace, a rotatable spider having arms adapted for supporting material in the furnace, the arms being adapted for cooling, and washer like members fitting over the arms and effective for holding material out of direct contact with the arms.

20 In testimony whereof I have hereunto set my hand.

LEIF LEE.
